UNITED STATES PATENT OFFICE.

WILLIAM MALLORY, OF TOPEKA, KANSAS.

OIL-BURNER.

1,276,939.

Specification of Letters Patent. Patented Aug. 27, 1918.

Application filed March 26, 1918. Serial No. 224,811.

To all whom it may concern:

Be it known that I, WILLIAM MALLORY, a citizen of the United States, residing at Topeka, in the county of Shawnee and State of Kansas, have invented certain new and useful Improvements in Oil-Burners, of which the following is a specification.

This invention relates to oil burners and the object of the invention is to provide a simple and efficient apparatus by the use of which coal oil or similar fuel will be rapidly and thoroughly vaporized and consumed. A further object of the invention is to provide an oil-burning apparatus which may be also utilized to burn coal, wood, or other solid fuel. The invention also seeks to utilize the heat thus produced in an advantageous manner.

The invention is illustrated in the accompanying drawings and consists in certain novel features which will be hereinafter first fully described and then particularly pointed out in the appended claims, and in the said drawings:

25 Figure 1 is an elevation of an oil burner embodying my improvements.

Fig. 2 is an enlarged vertical section of the same.

30 Fig. 3 is an enlarged vertical section of the burner plate and the parts coöperating therewith.

Fig. 4 is a plan view of the burner plate.

Fig. 5 is a detail perspective view of the ignition or ash pan.

35 Fig. 6 is a detail of a portion of the drum.

Fig. 7 is a view partly in elevation and partly in section showing an arrangement whereby my improved burner may be used in a house heating system.

40 Fig. 8 is a detail horizontal section on the line 8—8 of Fig. 7.

Referring more particularly to the drawings, the reference numeral 1 indicates a base or support in which is a door 2 provided with a damper 3 of a well-known type. Upon the base 1 is supported a drum or casting consisting of an outer wall 4 and an inner wall 5 which is constructed with a horizontal annular flange 6 at its lower end in which are openings 7. The said flange 6 is provided at its outer edge with a bead or other form of slight projection 8 which serves to center the outer wall 4. The inner wall 5 is provided with a plurality of openings 9 therethrough so that air may reach the coil 10 disposed at the inner side of said

wall and supported by brackets 11 on the base 1. A cover 12 is supplied upon the drum and supported upon the upper end of the outer wall 4, this cover being provided with an escape flue 13 and with a door 14 providing means for inserting coal, wood or other solid fuel into the device. The coil 10 forms a portion of the vaporizing apparatus and at its lower end is equipped with a nozzle 15 disposed centrally of the base 1. The upper end of the coil is connected with an oil supply pipe 16 by a coupling 17 which also receives a terminal of an air supply pipe 18. This air supply pipe 18 leads from a compressed air reservoir or tank 19 and has a branch 20 which leads into the nozzle 15. A valve 21 is fitted in the pipe 18 near the coupling 17 and a valve 22 is fitted in the branch 20 between the pipe 18 and the nozzle 15 as shown. The oil is contained in a tank or reservoir 23 from which the pipe 16 leads and a cut-off valve 24 is provided in said pipe to control the flow from the tank to the coil. A pipe 25 leads from the top of the air reservoir 19 into the top of the oil tank 23 and a valve 26 is fitted in said pipe to control the flow through the same.

A valve casing 27 is interposed in the nozzle 15 and in the said casing is mounted a 85 needle valve 28 by which the flow of vapor to the burner 29 is controlled, the stem 30 of the said valve 28 being elongated so as to project through the base as is clearly shown. The burner plate consists of a 90 central hub 31 secured directly on the lower end of the nozzle 15 and having its lower end closed and constructed to present a conical or tapered deflector 32 which projects somewhat into the lower extremity of 95 the nozzle, as shown clearly in Fig. 3. From the said hub a plurality of arms or tubes 33 radiate to a rim 34 and the bores and hollow passages of the said arms are extended downwardly through the said rim and open 100 through the lower edge of the same, as shown at 35 in Fig. 3. An ash pan or ignition pan 36 is suspended on and below the burner plate and to this end the said ash pan or ignition pan is equipped at diamet- 105 rically opposite points with radial projec- tions or lugs 37 adapted to be engaged over the hooks 38 formed on the under side of the burner plate as shown and as will be readily understood. A lining or shell 38 is 110 placed within the coil 10 and rests at its lower end upon the burner plate so as to con-

stitute a fuel basket or fire box when solid fuel is to be used. The said shell 38 may be of any preferred material and is provided throughout its extent with openings 38' so as to permit the heat to play upon the coil 10 while at the same time the shell or lining will hold the solid fuel out of contact with the coil and prevent injury to the coil from such source. The upper end of the lining 38 10 is flared or curved outwardly so as to project over the coil as shown at 39, and thereby forms a shield for the coil to prevent coal or wood lodging thereon when being inserted into the fuel basket. To provide a 15 support for the solid fuel, a grate 39' is fitted in the shell just above the nozzle 15, the fuel being thus held off the burner while the spaces between the radial arms 33 of the burner provide means for the ashes to 20 fall through the ash pit formed by the lower portion of the base 1.

The operation is thought to be clear from what has been said. It may be stated, however, that when it is desired to burn oil, the 25 valves 26 and 24 are opened so that air under pressure will be admitted to the top of the tank 23 and, by playing upon the surface of the oil in said tank, will force said fuel through the pipe 16 into the coil 10. Air 30 may be admitted to the top of the coil, by opening the valve 21, to mingle with the oil and aid in the vaporization of the same and, if the oil should be very heavy, additional air may be admitted into the nozzle 15 by 35 opening the valve 22 so that the vapor will be thin and readily ignited when it issues from the openings 35 in the burner plate. When starting a fire, a small quantity of oil is permitted to flow into the pan 36 after 40 which the valve 28 is closed so as to cut off the flow. The oil upon the pan 36 is ignited and the flame therefrom will play directly on the burner plate so as to heat the same, the result being that the oil which subse- 45 quently flows through the plate will be thoroughly vaporized and will be instantly ignited when it issues from the burner plate. This initial igniting charge of oil having been consumed, the valve 28 is again opened 50 and the vapor ignited at the openings 35, the intensity of the flame being controlled by regulation of the valve 28 as will be readily understood. The flame will rise past the burner plate and play upon the 55 coil 10 so that said coil will quickly become heated and the oil flowing through the same will be vaporized so that combustion will be complete at the edge of the burner plate. Air will be drawn in through the openings 60 7 and will rise through the drum to mingle with the flame at the upper edge of the inner wall 5, the shield 39 serving also as a deflector to turn the flame toward the drum as will be evident. As the air mingles with 65 the flame at the upper end of the drum, a

very hot blue flame will be produced so that a large quantity of heat will be furnished with a minimum consumption of fuel. The heat may be carried off through the flue 13 to any point of use or the cover 12 may be 70 removed and the heat permitted to dissipate and distribute itself as it emerges from the drum.

In Fig. 7 I have illustrated a mode of utilizing the heat from my burner in a 75 house-heating system. Upon the upper end of the wall 4 is placed a hollow wall casing 40 having openings 41 in its lower end through which air may rise to be heated while within the casing and finally pass out 80 through hot air flues 42 to any part of the house. Within the casing is arranged a coil 43 containing water and obviously exposed to the direct action of the heat rising from the burner. The inlet pipe 44 and the outlet pipe 45 of this coil are equipped with valves 46 and a drain 47 may also be provided. A water tube gage 48 may be fitted in the coil in the event that it is to be used with a steam generator and a pressure gage 90 49 and safety valve 50 may also be provided therefor. A fuel feed door 51 may be provided in the top of the drum and an ordinary swinging door 52 may be provided on the front of the drum near the lower end 95 of the same to permit removal of clinkers and inspection of the flame.

Having thus described the invention, what is claimed as new is:

1. An apparatus for the purpose set forth 100 comprising a coil, means for supplying oil to the upper end of the coil, means for supplying air to the upper end of the coil, a burner plate secured to the lower end of the coil and in communication therewith, means 105 for admitting air into the lower end of the coil, and means for controlling flow from the coil into the burner plate.

2. An apparatus for the purpose set forth 110 comprising a coil, a shell inserted through the coil and forming a lining therefor, a burner plate supported by the lower end of the coil and supporting the lower end of the shell, means for supplying fuel to the coil, and means for controlling the flow of 115 fuel from the coil into the burner plate, the burner plate being so arranged that flame therefrom will play upon the coil.

3. An apparatus for the purpose set forth 120 comprising an annular burner, a shell resting at its lower end upon and rising from the burner and having its upper end flared, the edge of the burner being beyond the shell, a coil around said shell over the edge of the burner and extending to the flared 125 upper end of the shell and having its lower end extended into the shell and connected to the burner, means for supplying fuel to the coil, and means for controlling the flow of fuel from the coil to the burner.

4. An apparatus for the purpose set forth comprising a base, a double-walled drum supported on the base and provided with openings in its lower end beyond the base 5 and through its inner wall, the outer wall of the drum being imperforate, a coil supported at the inner side of the inner wall of the drum, a burner within the base connected to the coil, means for supplying fuel 10 to the coil, and means for controlling the flow of fuel from the coil to the burner.
5. An apparatus for the purpose set forth comprising a base, a drum supported on the base and provided with openings in its inner 15 wall and its lower end beyond the base, a burner disposed within the base, a shell resting on and rising from the burner, a coil disposed between said shell and the drum and connected with the burner, means for supplying fuel to the coil, and means for 20 controlling the flow of fuel from the coil to the burner.
6. In an apparatus for the purpose set

forth, the combination of an oil reservoir, a compressed air reservoir, means for establishing a flow of air from the compressed air reservoir into the oil reservoir, a coil connected with the oil reservoir, means for controlling the flow of oil into the coil, means for admitting air to the upper end of the coil, a burner carried by and communicating with the lower end of the coil, means for admitting air to the lower end of the coil, and means for controlling the flow of fuel from the coil to the burner. 35

7. In an apparatus for the purpose set forth, the combination of a coil having its lower end located on its axis, a burner comprising a hub secured to the lower end of the coil and provided with a deflector entering the end of the coil, a rim and spaced tubes radiating from the hub to the rim and having their bores extended through the rim. 40

In testimony whereof I affix my signature. 45
WILLIAM MALLORY.
